UNITED STATES PATENT OFFICE.

GEORGE E. HULSE, OF NEWARK, NEW JERSEY, ASSIGNOR TO THE SAFETY CAR HEATING & LIGHTING COMPANY, A CORPORATION OF NEW JERSEY.

SYSTEM OF ELECTRICAL DISTRIBUTION.

Application filed April 13, 1920. Serial No. 373,829.

To all whom it may concern:

Be it known that I, GEORGE E. HULSE, a citizen of the United States, and a resident of Newark, in the county of Essex and State of New Jersey, have invented an Improvement in Systems of Electrical Distribution, of which the following is a specification.

This invention relates to systems of electrical distribution and with regard to the 10 more specific features, to systems of such nature peculiarly adapted for use in the lighting of railway cars. One of the objects thereof is to provide a simple and practical system of the above type adapted for efficient control of the generator output. Another object is to provide a system of the above type in which the charging current possesses certain desired characteristics and which is well adapted to meet various conditions of use. Other objects are to provide 20 systems of the above type in which the apparatus is readily adjustable to meet changing conditions of use or change of the type of battery used therein. Other objects will 25 be in part obvious and in part pointed out hereinafter.

The invention accordingly consists in the features of construction, combinations of elements and arrangement of parts which 30 will be exemplified in the structure hereinafter described and the scope of the application of which will be indicated in the following claims.

In the accompanying drawings in which 35 is shown one of various possible embodiments of this invention,

Figure 1 is a diagrammatic plan of the same;

Figure 2 is a cross section taken through 40 adjacent regulating coils of the apparatus shown in Figure 1 together with associated parts, and

Figure 3 is a sectional view taken along the line 3-3 of Figure 2.

Similar reference characters refer to similar parts throughout the several views of 45 the drawings.

Referring now to Figure 1 of the drawings, there is shown a generator 10 preferably driven at variable speed from the axle of a railway car. Serially positioned in the circuit of the shunt field 11 of this generator is a variable resistance 12 comprising a plu-

rality of contacting carbon disks, the aggregate resistance of which varies inversely 55 with pressure exerted thereon.

From the generator 10 the main 13 leads first through a series or current regulating coil 14, then through the ordinary automatic switch 15 of car lighting systems. At 16 is 60 a storage battery bridged across the mains 13 and 17 and the latter conductors are extended to connect with the generator in parallel with the battery the usual lamps 18. Interposed in one of the mains between the 65 battery and lamps are the usual hand controlled switch 19 and automatically controlled voltage regulator, diagrammatically indicated at 20.

Considering now the generator regulator, 70 there is shown a lever 21 pivoted at 22 and provided with an outwardly extending arm 23. A suitable adjustable retracting spring 24 is so arranged as to tend to throw the adjacent end of the lever 21 upwardly and 75 cause the arm 23 to exert pressure upon the carbon pile 12 and reduce its resistance. Connected with the opposite end of the arm 21 is a core 21' attracted and controlled jointly and cumulatively by the magnetic 80 field of the current regulating coil 14 and a voltage regulating coil 14'. The latter coil is bridged across the generator from its lower terminal to the point 25 in the main 13. 85

As the aggregate field of these two coils increases, it tends to raise the core 21', overcoming spring 24 and lessening the pressure upon the carbon pile 12 and hence the aggregate resistance of the latter. A weakening 90 of this aggregate field will obviously tend to have the opposite effect.

Mounted adjacent the lever 21 is a lever 26. These levers although shown vertically displaced in the diagrammatic Figure 1, are 95 preferably in actual use side by side as indicated in Figure 2, the pivot 27 of the lever 26 being substantially in alignment with the pivot of lever 21. Lever 26 is provided with an adjustable retracting spring 28 at one 100 end, and at its opposite end with a core 29 connected therewith as hereinafter described. This core is attracted by a voltage coil 30 connected across the generator in substantially the same manner as the voltage coil 21' except that it has serially in- 105

cluded in its circuit a manually adjusted variable resistance element 31. Lever 26 is provided with a lug 32 adapted to co-act with a similar lug 33 upon the lever 21 when the core 29 is drawn upwardly by the coil 30. When this action occurs and the levers 32 and 33 are engaged one with the other and thus in effect mechanically connected, the movement of the arm 23 and accordingly the resistance of the carbon pile 12 are under the joint control of the coils 14, 21' and 30.

In order that the core 29 may have a considerable range of movement away from its uppermost position and yet the apparatus be compactly disposed, the end of the lever 26 is pivotally connected thereto as illustrated in Figures 2 and 3 of the drawings. The lower end of the core is slotted as at 34 and has positioned within this slot a pair of links 35 upwardly extending and provided with co-axial pivots 36. The end of the lever 26 is pivotally connected as by the pin 37 between these links. In this manner free movement is provided for the swinging of the end of the arm 26 about its pivot 27, and yet the core 29 may have its metal so disposed as to give the desired range of pull with a given range of excitation of the coil. A similar connection may be used if desired to connect the lever 21 with the lower end of the core 21'.

The method of mounting of the core 29 within its coil may be briefly referred to. At the lower end it slides within a bushing 38 and at its upper end its reduced extension 39 slides within a bushing 40. This latter bushing is provided with a substantially semi-circular abutment 41 adapted to fit within a corresponding recess 42 in a collar 43 which is secured to the part 39. With the parts as shown in Figure 3 of the drawings, the downward movement of the core is not terminated until the abutment 41 rests within recess 42 and abuts against its end wall. If however it is desired that the downward movement of the core be limited to a higher position within the coil, the collar 43 is simply rotated about the axis 45 of the core so as to bring the recess 42 out of registry with the abutment 41. With the parts so placed, the lowermost position of the core is that in which the upper end of the abutment 41 contacts the unrecessed portion of the collar 43. In the drawings the core is shown in intermediate position.

By the use of this adjustment, the core 29 is raised out of its lowermost position and into regulating action with a lesser excitation of the coil 30 when abutment 41 is out of registry with recess 42 than is required when these parts are in registry and the core rests in a lower position. Thus for this reason with a lead battery, where it is desired to bring the core 29 into regu-

lating action at a lower generator voltage than with an Edison battery, the collar 43 is so adjusted as to prevent an extreme downward motion of the core. If however, an Edison battery is used and it is desired to keep the core 29 out of regulating action until a higher voltage is reached, then the parts are adjusted as shown in Figure 3 of the drawings, permitting the core to rest in its lowermost position. 75

There is another feature of construction which should be noted prior to the general description of the action of the apparatus. As shown in Figure 2 of the drawings, the two regulating units are connected one with another at their lower ends by an iron plate 44. This plate performs a highly desirable function in tying the units together more closely in a magnetic sense, or, in other words, developing their magnetic inter-action 85 one upon the other. The effect of this will be hereinafter noted.

Considering now the action of the apparatus as a whole, and assuming that the generator is started with a substantially discharged battery: At or about a predetermined speed of the generator, the automatic switch 15 will close and the charge of the battery will start. Under these conditions, the current flow in the coil 14 will be large and the generator voltage required to occasion such flow, will be relatively small. The voltage of the coil 30 will be insufficient to raise its core 29. Thus regulation may be carried on at first largely by coil 14 but with important and increasing direct effect from the coil 14'. Excessive flow of current is thus prevented, and also a large voltage excess is prevented by the continuously active voltage coil 14'. As the back electromotive force of the battery builds up, the generator voltage will also increase and the coil 14' gain strength. This will result in a tendency to give a gradually decreasing current output during the main part of the charge, which has many advantages. This decrease, however, is prevented from becoming too sharp by the magnetic inter-action above described, of the coil 30. The flux of this coil, although it is not effective through its own core 29, nevertheless bucks the flux of the coils 14 and 14' to an increasing extent as the charge progresses, and requires them to maintain a greater magneto force than would otherwise be the case. By a careful proportioning of the coil and magnetic inter-action, precisely the desired current curve may be attained and all disturbing influences effectively remedied, even though of an abnormal nature. 110

When the battery has reached an advanced state of charge, the coil 30 will have developed sufficient field of its own to raise its core 29 and bring the lugs 32 and 33 into interlocking relation. After this 120 125 130

10 cures, the control is jointly by all three regulating coils with a progressive increase in power of the voltage coil and decrease in power of the current coil. This will prevent any large increase in generator voltage thereafter, and the current will be tapered off in the most approved manner, thus effectively protecting the battery. Furthermore in the second stage or after the levers 15 are connected, this magnetic inter-action has another advantage of marked importance. In this stage the falling strength of the current regulating coil as the current is tapered off, correspondingly decreases a tendency to buck the flux of the voltage regulating coil 30 and thus facilitates the action of the latter in tending to prevent rise of voltage as its pull upon its armature increases to make up for the loss of pull of 20 the current coil 14.

If it is desired to substitute a lead battery for an Edison battery, or the reverse, the nut or collar 43 is simply twisted as hereinbefore explained to adjust the lowermost position 25 of the coil 29, and preferably the strength of the coil 30 for a given voltage is adjusted to a new value by means of the manually variable resistance element 31.

It will thus be seen that there is provided 30 apparatus in which the several objects of this invention are achieved and that by proper relative and absolute proportioning of the three regulating coils for their direct and indirect action, the current and voltage of the 35 generator output are so controlled as to carry on the charging at all stages at the desired rate and to meet any contingencies which may arise in use.

As various possible embodiments might be 40 made of the above invention and as various changes might be made in the embodiment above set forth, it is to be understood that all matter herein set forth or shown in the accompanying drawings is to be interpreted 45 as illustrative and not in a limiting sense.

I claim as my invention:—

1. In systems of the class described, in combination, a generator driven at a variable speed, a storage battery adapted to be charged thereby, a current coil through which current passes from said generator to said battery, a voltage coil connected to present a field substantially proportional to the voltage of said generator, means adapted to regulate said generator under control of said coils acting jointly, a second voltage coil connected to present a field substantially proportional to the voltage of said generator, and means co-acting with said last coil 55 adapted upon the field of said last coil attaining sufficient strength to co-act with said first regulating means in regulating said generator.

2. In systems of the class described, in 60 combination, a generator driven at a va-

riable speed, a storage battery adapted to be charged thereby, a current coil through which current passes from said generator to said battery, a generator voltage coil, means controlled by said coils and acting to regulate 70 said generator, a second generator voltage coil, and a device controlled thereby and adapted upon the field of said second voltage coil attaining sufficient strength to add its pull to said regulating means and co-act 75 therewith in the regulation of the generator.

3. In systems of the class described, in combination, a generator driven at a variable speed, a storage battery adapted to be charged thereby, a current coil through 80 which current passes from said generator to said battery, a generator voltage coil, a carbon pile connected in the field of said generator, a device magnetically controlled by said coils acting cumulatively to vary the 85 pressure upon said carbon pile and regulate said generator, a second generator voltage coil, and means controlled thereby, adapted upon the field of said coil attaining sufficient strength to transmit mechanically its effect 90 to said first regulating means and co-act therewith in the regulation of the generator.

4. In systems of the class described, in combination, a generator driven at a variable speed, a storage battery adapted to be charged thereby, a current coil through which current passes from said generator to said battery, a device magnetically acted upon by said coil adapted to regulate said 95 generator, a generator voltage coil, a device magnetically acted upon thereby, adapted upon the field of said voltage coil attaining sufficient strength to transmit mechanically 100 its effect to said first device and co-act therewith in the regulation of the generator, and magnetic means connecting the fields of said coils one with another whereby the field of said current coil tends to reduce the flux due 105 to said voltage coil.

5. In systems of the class described, in combination, a generator driven at a variable speed, a storage battery adapted to be charged thereby, a current coil through which current passes from said generator to said battery, a device magnetically acted upon by 110 said current coil adapted to regulate said generator, a generator voltage coil, a device magnetically acted upon thereby, adapted upon the field of said voltage coil attaining sufficient strength to transmit mechanically 115 its effect to said first device and co-act therewith in the regulation of said generator, and means adapted upon such joint regulation proceeding, to increase the regulating effect of said voltage coil with respect to that of 120 said current coil at a rate greater than the rate of change of the relation of their respective ampere turns.

6. In systems of the class described, in combination, a generator driven at a vari- 130

- able speed, a storage battery adapted to be charged thereby, a current coil through which current passes from said generator to said battery a voltage coil connected to present a field substantially proportional to the voltage of said generator, means adapted to regulate said generator under control of said coils acting jointly, a second voltage coil connected to present a field substantially proportional to the voltage of said generator, and means co-acting with said last coil adapted upon the field of said last coil attaining sufficient strength to co-act with said first regulating means in regulating said generator, said second voltage coil being more powerful than said first voltage coil.
7. In systems of the class described, in combination, a generator driven at a variable speed, a storage battery adapted to be charged thereby, a current coil through which current passes from said generator to said battery, a generator voltage coil, means controlled by said coils and acting to regulate said generator, a second generator voltage coil, and a device controlled thereby and adapted upon the field of said second voltage coil attaining sufficient strength to add its pull to said regulating means and co-act therewith in the regulation of the generator, said second voltage coil being more powerful than said first voltage coil.
8. In systems of the class described, in combination, a generator, a storage battery adapted to be charged thereby, a current coil through which current from said generator passes, means acted upon by said current coil adapted to regulate the generator, a generator voltage coil, means acted upon by said voltage coil normally ineffective upon said regulating means but adapted to be brought into co-action therewith upon the field of said voltage coil attaining sufficient strength, and means adapted in two alternative positions to change the degree of field strength of said voltage coil required to bring its associated parts into regulating action.
9. In systems of the class described, in combination, a generator, a storage battery adapted to be charged thereby, a current coil through which current from said generator passes, means acted upon by said current coil adapted to regulate the generator, a generator voltage coil, means acted upon by said voltage coil normally ineffective upon said regulating means but adapted to be brought into co-action therewith upon the field of said voltage coil attaining sufficient strength, means acted upon by said voltage coil comprising a core with which said coil co-acts, and means adjusting the retracted position of said core with respect to said coil.
10. In systems of the class described, in

combination, a generator, a storage battery adapted to be charged thereby, regulating apparatus for said generator comprising a generator voltage coil, a core positioned within the field of said coil and a lever, said core being recessed at its end remote from said coil and having the end of said lever therein and connected thereto by a link connection.

11. In systems of the class described, in combination, a generator, a storage battery adapted to be charged thereby, regulating apparatus for said generator comprising a generator voltage coil, a core positioned within the field of said coil, and a lever, said core and the adjacent end of said lever having a link connection one with another to permit relative rotary and transverse movements of their ends.

12. In systems of the class described, in combination, a generator driven at a variable speed, a storage battery adapted to be charged thereby, a current coil through which current passes from said generator to said battery, a generator voltage coil, a carbon pile connected in the field of said generator, a lever adapted by its movement to vary pressure on said pile, a core connected with said lever and positioned within the magnetic field of both of said coils, a second generator voltage coil, a lever adapted upon being moved to come into a relation in which it transmits mechanically its effect to said first lever and co-act therewith in controlling the pressure on said carbon pile, and a core connected with said second lever and so related to said second voltage coil as upon the field of the latter attaining a strength indicating a substantial degree of charge of the battery to be moved thereby and bring said lever into said relation to transmit mechanically its effect to said first lever.

13. In systems of the class described, in combination, a generator driven at a variable speed, a storage battery adapted to be charged thereby, a current coil through which current passes from said generator to said battery, a generator voltage coil, a carbon pile connected in the field of said generator, a lever adapted by its movement to vary pressure on said pile, a core connected with said lever and positioned within the magnetic field of both of said coils, a second generator voltage coil, a lever adapted upon being moved to come into a relation in which it transmits mechanically its effect to said first lever and co-act therewith in controlling the pressure on said carbon pile, and a core connected with said second lever and so related to said second voltage coil as upon the field of the latter attaining a strength indicating a substantial charge of the battery to be moved thereby and bring said lever into said relation to transmit

mechanically its effect to said second lever, said second voltage coil being of greater strength than said first voltage coil.

14. In systems of the class described, in combination, a generator driven at a variable speed, a storage battery adapted to be charged thereby, a current coil through which current passes from said generator to said battery, a generator voltage coil, a carbon pile connected in the field of said generator, a lever adapted by its movement to vary pressure on said pile, a core connected with said lever and positioned within the magnetic field of both of said coils, a second generator voltage coil, a lever adapted upon being moved to come into a relation in which it transmits mechanically its ef-

fect to said first lever and co-act therewith in controlling the pressure on said carbon pile, a core connected with said second lever and so related to said second voltage coil as upon the field of the latter attaining a strength indicating a substantial charge of the battery to be moved thereby and bring said lever into said relation to transmit mechanically its effect to said second lever, said second voltage coil being of greater strength than said first voltage coil, and a magnetic connection whereby the fields of said several coils are inter-connected.

In testimony whereof, I have signed my name to this specification this 8th day of April, 1920.

GEORGE E. HULSE.
